CLAIM

The ornamental design for handle assembly for vehicles, as
shown and described.

DESCRIPTION

FIG. 1 is a perspective view of a handle assembly for
vehicles according to the present invention;

FIG. 2 is a front view of the handle design of FIG. 1;

FIG. 3 is a right side view of the handle design of FIG. 1;

FIG. 4 is a left side view of the handle design of FIG. 1;

FIG. 5 is a top side view of the handle design of FIG. 1;

FIG. 6 is a rear view of the handle design of FIG. 1;

FIG. 7 is a bottom side view of the handle design of FIG. 1;
and,

FIG. 8 is a front view of the handle design of FIG. 1 in an
alternate position, with the mounting plate rotated relative to

the handle 90 degrees from the position shown in FIG. 2.

The broken lines (specifically those showing mounting
holes, the key cylinder, and the drive shaft) are provided to
show the bounds of the claimed design and thus form no part
of the claimed design.
